UNITED STATES PATENT OFFICE.

JOHN WEENE, OF SCHENECTADY, NEW YORK, ASSIGNEE TO WHEELS ELECTRIC COMPANY, OF SCHENECTADY, NEW YORK, A CORPORATION OF NEW YORK.

PORCELAIN SOCKET.

1,232,250.

Specification of Letters Patent. Patented Jan. 26, 1917.

Application filed October 27, 1914. Serial No. 382,351.

To all whom it may concern:

Be it known that I, JOHN WEENE, a citizen of the United States, residing at Schenectady, county of Schenectady, and State of New York, have invented certain new and useful Improvements in Porcelain Sockets, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a view in side elevation of an incandescent electric lamp-socket embodying my invention as applied 26 to a key-socket.

Fig. 2 is a view partly in side elevation and partly in vertical section of the same with a pull-socket-unit substituted for the key-socket-unit within the casing of the 25 socket.

Fig. 3 is a top plan view of the sleeve of the socket-casing with the cap removed.

Fig. 4 is a central, vertical section of the same taken on the broken line 4-4 in 30 Fig. 3.

Fig. 5 is a bottom plan view of the cap of the casing.

Fig. 6 is a central, vertical section of the cap taken on the broken line 6-6 in Fig. 3.

Fig. 7 is a view in side elevation of a key-socket-unit adapted to be contained within my improved socket-casing interchangeably with a pull-socket-unit or a keyless-unit.

Fig. 8 is a similar view of the pull-socket-unit.

Fig. 9 is a similar view of the keyless-unit.

Fig. 10 is a horizontal cross-section of a complete socket containing the keyless-unit.

This invention relates to sockets particularly adapted for outdoor use, having a casing formed of rigid molded parts detachably secured together, a type of such socket being commonly known in the art as a porcelain socket.

As such porcelain sockets have heretofore

been constructed, it has been necessary, to meet the demand for key-sockets, keyless-sockets, and pull-sockets, to supply different complete constructions adapted for the respective needs, due to the fact that it was impossible in such constructions to substitute, one for another, the essential features of the key-socket, keyless-socket and pull-socket without entire re-construction of the whole device including the casing.

Certain objects of the present invention are to provide a casing of molded porcelain, or similar molded rigid insulating material, adapted to interchangeably receive the essential elements of a plurality or all of said key-

sockets, keyless-sockets, and pull-sockets; to provide a socket of this type, that is, a porcelain socket or the like, with exteriorly accessible means for detachably securing together the casing-members; and to provide

a socket of this type, that is, a porcelain socket or the like, with a removable unit comprising a base of insulating material and current-transmitting mechanism mounted upon said base, and with a separable casing,

the members of which are detachably secured together independently of said unit by means in addition to the casing-members.

Other objects will appear in connection with the following description:

Referring to the drawings wherein the invention is shown in preferred form, the casing of my improved socket comprises the sleeve, 1, and cap, 2, each formed of porcelain or other rigid molded insulating material, having means whereby said sleeve and cap are detachably secured together.

The sleeve, 1, is open from end to end and the interior of the sleeve is tapered or offset whereby it is contracted toward its outer end.

The sleeve thus formed is adapted to receive and support interchangeably a plurality of removable units, each unit complete in itself in that it comprises an insulating base and current-transmitting mechanism mounted upon and removable with said base.

The sleeve is provided with a longitudinal slot, 3, open at the inner end of the

sleeve, adapted to receive either the key-
stem, 4, of a key-socket-unit, 5, or the bell,
6, of a pull-unit, 7.

The interior of the sleeve, 1, is also pref-
erably provided with longitudinal grooves,
8, adapted to receive lugs or ribs, 9, on
the porcelain base of a keyless-unit, 19,
or similar lugs or ribs, 11, on the key-unit,
or 12 on the pull-unit to prevent relative
rotation between the casing and the casing-
inclosed-unit.

For most uses in practice, relative rotation
between the casing and either the key-
unit or the pull-unit is sufficiently limited
15 by the engagement of either the key-stem or
the bell, 6, with the walls of the slot, 3; and
if desired, the longitudinal grooves, 8, and
the lugs or ribs, 11, and 12, may be omitted
20 if the device is not intended for use as
a keyless-socket.

If the device is intended to be used only
as a keyless-socket, the slot, 3, may be omitted.

The cap, 2, is complementary to the sleeve,
25 1, to complete the inclosure for the casing-
contained unit, whether key, keyless or pull.

In the preferred form of casing shown,
the sleeve is provided in its outer surface
with longitudinal grooves, 13, and has on its
30 inner end lugs, 14, overhanging the respective
grooves, 13, and provided with apertures
adapted to receive the respective fastening
screws, 15, said grooves, 13, being of
a depth adapted to receive more or less of
35 said fastening screws, leaving the heads of
the screws exteriorly accessible.

The inner side of the cap, 2, is provided
with recesses, 16, and with apertures, 17, ex-
40 tends from the respective recesses, 16,
45 through the outer surface of the cap.

Located in each recess, 16, is a nut-plate,
18, provided with a screw-threaded aperture,
19, adapted to receive the neighboring
fastening screw, 15; and said nut-plate, 18,
45 is held within its recess, 16, by means of a
screw, 20, inserted through the aperture, 17,
into a screw-threaded aperture in said nut-
plate, 18.

After the nut-plates, 18, have been firmly
50 secured to the cap, 2, by tightly setting up
the screws, 20, the outer ends of the apertures,
17, are sealed up with pitch or cement
making the nut-plates, 18, a permanent part
of the cap, and the casing-members are sepa-
55 rated and secured together, as occasion de-
mands, by manipulation of the exteriorly ac-
cessible fastening screws, 15, which serve to
firmly secure together the casing-members,
while permitting the casing-members to be
60 readily separated or secured together with-
out the introduction of a screw-driver or
other tool within the sleeve, 1.

The cap, 2, is provided with a central ap-
erture, 21, for the circuit wires.

By the use of the grooves, 13, and the ap-
ertured lugs, 14, overhanging said grooves,
I am able to provide the casing with exte-
riorly accessible fastening means without
undue increase in the external dimensions of
the socket.

The exterior of the sleeve, 1, is preferably
formed with one or more peripheral flanges,
22, one of which extends across or adjacent
to the outer end of the respective grooves,
13, said flange and the overhanging lugs, 70
14, serving to reinforce the sleeve and to
compensate for any tendency to weakness
due to the presence of the grooves, 13.

In the preferred form of my invention as
illustrated, the grooves, 13, are provided 80
without any deduction from the space within
the sleeve, 1; and by forming the cap,
2, with lugs, 23, I am able to extend the
nut-plates, 18, to coöperate with the screws,
15, inserted in line with the grooves, 13, in 85
the sleeve, 1, with minimum external en-
largement of the cap.

Another result of my improved construc-
tion is that it enables me to make the casing-
inclosed units, such for example as shown in 90
Figs. 7, 8 and 9, interchangeable in the
sleeve, 1, and makes it possible to employ
interchangeable caps and cap-mountings for
porcelain sockets, with substantially the
same convenience and facility as heretofore 95
has been the case with metal-case sockets
only.

This last mentioned result is made possi-
ble by interchangeability of the casing-in-
closed units and the employment of means 100
in addition to the case-members themselves
for securing the case-members together inde-
pendently of the casing-inclosed units.

What I claim as new and desire to secure
by Letters Patent is:

1. An incandescent electric lamp-socket-
casing, having casing-members comprising a
cap and a sleeve, both made of rigid molded
insulating material, each of said members
being provided with an exteriorly-open ap-
erture; a screw inserted through said exte-
riorly-open aperture in said one casing-
member with its head accessible from the
outer side of said member; a nut carried
by the other casing-member in engagement 115
with said screw, and means inserted through
said open aperture in said other casing-
member for securing said nut thereto.

2. A casing for incandescent electric lamp-
sockets comprising in combination a rigid 120
sleeve of molded insulating material pro-
vided in its external periphery with a longi-
tudinal groove and having on its inner end
an apertured lug projecting across one end
of said groove; a cap adapted to be secured 125
upon said inner end of the sleeve, said cap
having a lug overlying said lug on the
sleeve; a nut-plate secured to the inner side

of said cap extending along said lug on the cap and provided with a screw-threaded aperture adapted to register with said aperture in the lug on the sleeve; and a screw inserted through said aperture in the lug on the sleeve engageable with the screw-threaded aperture in said nut-plate.

In testimony whereof, I have hereunto set my hand this 21st day of October, 1914.

JOHN WEBER.
